Primary Examiner — Susan Bennett Hattan*Assistant Examiner* — Suzanne E Tisdell(74) Attorney, Agent, or Firm — McCoy Russell LLP(57) CLAIM

The ornamental design for an oil filter housing, as shown and described.

DESCRIPTION

FIG. 1 is a perspective view of an oil filter housing according to an embodiment of the invention;

FIG. 2 is another perspective view thereof;

FIG. 3 is another perspective view thereof;

FIG. 4 is a front view thereof;

FIG. 5 is a rear view thereof;

FIG. 6 is a left view thereof;

FIG. 7 is a right view thereof;

FIG. 8 is a top view thereof; and,

FIG. 9 is a bottom view thereof.

The broken line portion of the figures is included to show unclaimed subject matter only and forms no part of the claimed design.
